UNITED STATES PATENT OFFICE

LEWIS GEORGE KITCAT, OF LONDON, ENGLAND

REMOVABLE BOOK COVER

Application filed May 27, 1930, Serial No. 456,046, and in Great Britain June 24, 1929.

This invention relates to removable book covers commonly known as book jackets or dust wrappers for protecting the binding of the book, of the kind that are of flexible material and adapted to be disposed around the permanent covers and back of the book and turned or folded around the edges (often referred to as the "fore-edges") of the covers, the terminal parts of the removable cover 5 being provided with stiffening strips or elements for disposal inside the permanent covers adjacent to the edges in order to retain the removable cover in place. With such covers it is found desirable to make the 10 removable cover of such a length as will ensure that the folds where the removable cover passes over the edges of the permanent covers occur in that portion of the removable cover immediately adjacent to the edge of 15 the stiffening strip or element which is secured to it. This is disadvantageous in that it renders necessary the maintaining of a certain standard of accuracy in the lengths of flexible material for the removable covers 20 and in attaching the stiffening strips or elements. A further disadvantage is that the portion of the removable cover which is secured to the stiffening strip or element—usually by an adhesive—is visible when the 25 cover of the book is open and is unsightly. The chief object of the invention is to obviate these disadvantages.

According to the invention a removable book cover of the kind set forth is of a size 30 such as to allow of the stiffening strip or element being turned underneath that part of the removable portion of the cover which lies on the inner side of the permanent cover of the book when the removable cover is in 35 position. The stiffening strip or element may be such that when the removable cover is placed on the book a portion of the stiffening strip or element passes around the edge of 40 the permanent cover of the book and between it and the removable cover and this portion may subsequently be on the inside of the permanent cover adjacent to the edge thereof. The stiffening strip or element may be 45 of stiff paper or card, and the removable 50

cover is preferably of transparent or translucent material.

In order that the said invention may be clearly understood and readily carried into effect the same will now be described more 55 fully with reference to the accompanying drawings, in which:—

Figures 1 and 2 are edge views of removable book covers and stiffening strips made in accordance with the invention. 60

Figure 3 is an edge view of a portion of a book showing the manner in which the removable book cover of Figure 1 is applied thereto and,

Figures 4 and 5 are similar views in respect of the cover of Figure 2. 65

Figures 6 and 7 are edge views of a portion of a book illustrating a modified form of the cover.

Figure 8 illustrates part of the edge of 70 the portion of the removable book cover which is secured to the stiffening strips.

A is the removable cover of which only the end portions are shown and B¹, B² the stiffening strips. The removable cover A 75 is of a transparent paper having a cellulose base and is secured to the strips B¹, B² by means of adhesive, the edge of the removable cover being serrated as shown in Figure 8 and being secured between the stiffening 80 strips B¹, B² and tabs b¹, b² respectively for the purpose of satisfactorily attaching the cover to the strips B¹, B². Transparent paper of the nature referred to is found to give rise to difficulty in that connection if 85 an attempt is made to secure a plain cover edge to a stiffening strip merely by the use of adhesive. The thickness of the removable cover A, strips B¹, B² and tabs b¹, b² is exaggerated in the drawings for the sake of 90 clearness. In the arrangement of Figures 1 and 3 the stiffening strips B¹, B² are each turned underneath that part of the removable cover A which lies on the inner side of the permanent covers C¹, C² of the book when 95 the removable cover is in position.

In the arrangements illustrated in Figures 2, 4 and 5 and Figures 6 and 7 a stiffening strip is such that when the removable cover is placed on the book a portion of the stiffen- 100

ing strip passes around the edge of the permanent cover of the book and between it and the removable cover. In the arrangement of Figures 2, 4 and 5 the tab b^2 is of greater width than the tab b^1 and is secured to the stiffening strip B^2 for only a part of its width the remainder of which forms virtually an extension of the strip B^2 . When the removable cover is applied to a book the stiffening strip B^1 is arranged on the inside of one of the permanent covers C^1 thereof so that the fold in the removable cover where it passes over the edge of the permanent cover C^1 is immediately adjacent to the edge 15 of the stiffening strip B^1 . The removable cover A is then drawn smoothly round the book and the other stiffening strip B^2 turned over the edge of the other permanent cover C^2 . The dimensions and arrangement of 20 the parts are such that a part b^{2x} of the tab b^2 will become folded over and will lie on the outside of the permanent cover C^2 and between it and the removable cover A. The condition of the removable cover and stiffening 25 strips at this stage is shown in Figure 4. The folded-over portion b^{2x} of the tab b^2 is now brought to the inside of the permanent cover C^2 as shown in Figure 5. It will be seen that the width of the folded-over portion of the tab b^2 is dependent on the length 30 of the removable cover, the attachment thereto of the stiffening strips, and the size of the book and that any inaccuracies or variations are automatically compensated 35 for by a variation in the width of the folded-over portion of the tab b^2 the folded edge of which is now correctly positioned. The presence of the tab b^2 also assists in obtaining tension on the removable cover A. In 40 the arrangement of Figures 6 and 7 the edges of the removable cover are secured to the edges of the stiffening strips B^1 , B^2 which are remote from the edges of the permanent book covers C^1 , C^2 and the folded-over portion b^{2x} , instead of being formed by 45 part of the tab b^2 , is in this case formed by the stiffening strip B^2 itself. The removable cover of Figures 6 and 7 is applied to the book in a similar manner to that of Figures 2, 4 and 5.

Instead of the edges of the removable cover A being serrated as described above, rows of holes may be formed therein close and parallel to the edges thereof. If, however, a suitable adhesive is available or the material of the removable cover such as to be readily secured to the stiffening strips by an adhesive, the edges of the removable cover might be plain and tabs such as b^1 , b^2 might moreover be unnecessary. Furthermore, the portion b^{2x} might be left in the positions indicated in Figures 4 and 6 respectively although it is preferred to arrange them on the inside of the permanent book cover as in Figures 5 and 7.

The face of the stiffening strip which is visible when the permanent book covers are opened may have advertising matter thereon, or a strip of paper having advertising matter thereon may form part of or be secured to the front stiffening strip so as to lie between the front permanent cover of the book and a transparent removable cover so that the matter is visible through the latter.

What I claim and desire to secure by Letters Patent of the United States is:—

1. A removable book cover, comprising a sheet of flexible material adapted for disposal around the permanent covers and back of a book, and stiffening elements on the terminal parts of said removable cover for disposal inside said permanent covers, the removable cover being of such a size as to permit one of the stiffening elements being turned underneath that part of the removable book cover which lies on the inner side of the permanent cover of the book when the removable cover is in position.

2. A removable book cover, comprising a sheet of flexible material for disposal around the permanent covers and back of a book, and stiffening strips secured to the terminal parts of said removable cover and disposed inside said permanent covers, the removable cover being of such a size as to permit one of the stiffening strips being turned underneath that part of the removable book cover which lies on the inner side of the permanent cover of the book when the removable cover is in position.

3. A removable book cover, comprising a sheet of flexible material for disposal around the permanent covers and back of a book, and stiffening elements on the terminal parts of said removable cover for disposal inside said permanent covers, the removable cover being of such a size as to allow of one of the stiffening elements being turned underneath that part of the removable book cover which lies on the inner side of the permanent cover of the book when the removable cover is in position, the stiffening element being such that when the removable cover is placed on a book a portion of the stiffening element passes around the edge of the permanent cover of the book and between it and the removable cover.

4. A removable book cover as in claim 3, in which the said portion of the stiffening strip is subsequently arranged on the inside of the permanent cover adjacent the edge thereof.

5. A removable book cover, comprising a sheet of flexible material adapted for disposal around the permanent covers and back of a book, stiffening strips for disposal inside said permanent covers, and tabs therefor, the terminal parts of said removable cover being secured between said tabs and said stiffening strips and the removable cover

being of such a size as to allow of a stiffening strip being turned underneath that part of the removable book cover which lies on the inner side of the permanent cover of the book when the removable cover is in
5 position.

6. A removable book cover as in claim 5, in which the terminal parts are serrated and have perforations adjacent the edges, said parts being secured between a stiffening
10 strip and one of the tabs by means of adhesive.

15 7. A removable book cover, comprising a sheet of flexible material adapted for disposal around the permanent covers and back of a book, stiffening strips for disposal inside said permanent covers, and tabs therefor, the terminal parts of said removable cover being secured between said tabs and said stiffening strips and one of said tabs
20 being so arranged that when the cover is placed on the book a portion of the tab passes around the edge of the permanent cover of the book and between it and the removable cover.
